UNITED STATES PATENT OFFICE.

FRANK R. CARGILL, OF CHICAGO, ILLINOIS.

JOURNAL-BEARING.

SPECIFICATION forming part of Letters Patent No. 651,563, dated June 12, 1900.

Application filed January 23, 1899. Serial No. 703,087. (No model.)

To all whom it may concern:

Be it known that I, FRANK R. CARGILL, a citizen of the United States, residing at Chicago, in the county of Cook and State of Illinois, have invented certain new and useful 5 Improvements in Journal-Bearings, of which the following is a specification.

The object of this invention is the production of a journal-bearing wherein the initial 10 embedment-pressure is given to the bearing before its application to the journal and the fiber of the metal thus condensed and solidified, wherein also the bearing-surface is smoothed without being cut away or in any 15 way deprived of its skin or surface, and wherein in any warping or misshape of the bearing is corrected.

In the accompanying drawings, Figure 1 is a plan view of an apparatus employed in the 20 production of my improved journal-bearing. Fig. 2 is a vertical central section through said apparatus. Fig. 3 is a detail view of a yielding side bar and its connections. Fig. 4 is an end elevation of a lined "brass" for 25 railway journal-bearings. Fig. 5 is a like view of a filled brass shell, and Fig. 6 a similar view of a solid brass for journal-bearings.

Like letters of reference indicate corresponding parts throughout the several views. 30 This invention applies to any journal-bearing, but is here particularly shown in its application to the journal-bearings of railway-cars. As is well known, the portion of the journal-bearing of railway-cars, either steam 35 or tram cars, which bears the weight of the car and its load upon the journal is a removable and renewable semitubular piece of metal, and on account of its having almost universally been made of brass is called a 40 "brass." Brasses as heretofore made were cast in sand molds and bored or ground out to the proper size. Some were faced on their bearing-surface with a sheet of antifriction metal and in others a shell of brass was filled 45 with an antifriction alloy; but the two latter styles have never proved satisfactory, from the fact that the soft antifriction metal when subjected to the enormous and constantly-increasing weight of modern cars and their 50 loads "squashes out," for which reason the solid brass has been for many years the only practical journal-bearing for railway-cars.

As stated above, these brasses have been prepared for use by boring them out in a lathe or boring-mill, which method is expensive 55 and not particularly well adapted to the production of a perfect form in the brass, or by grinding them out on an emery-roll, which is far more objectionable than the boring, inasmuch as it is less accurate and grains of 60 the emery are liable to become embedded in the bearing-surface and cause cutting and much friction in the journal when the brass is put into use. In addition to these objections, one common to both ways of preparing the 65 brasses is that the tough outer skin of the metal is cut away, leaving the heart or interior thereof exposed to the first wear of the journal. The outer skin of the metal is much more enduring and provides a fine bearing- 70 surface when it can be smoothed properly for use.

The initial embedment-pressure on journal-bearings in practice is the pressure exerted 75 upon the bearing by the weight of the car and its load, and it has been found that until brasses or any journal-bearings have received this initial pressure and have been conformed thereby to the journal much more friction results than after the journal-bearings have been so conformed by wear or pressure. 80 In the application of my invention I apply the initial embedment-pressure to the journal-bearing before it is placed upon the journal, the amount of pressure so applied 85 being limited only by the endurance of the metal composing the brass, and any degree of pressure which shall be found to best fit the brass for service may be given to it. I have found that about twice the pressure which it 90 would sustain under the heaviest load likely to be imposed upon the bearing is sufficient as an initial embedment-pressure. This initial embedment-pressure also condenses the 95 fiber of the metal composing the journal-bearing, and thereby makes a tougher and more lasting bearing-surface.

In the production of my improved brass I employ a hydraulic or other press apparatus which I will now describe, and wherein A is 100 the bed of the press, and A' the pressure-piston thereof. A bed-block A² is rigidly secured to the bed near the end opposite to the piston A'. In the bed-block is provided a re-

movable form-seat A³ for adapting the press to the different exterior forms of brasses and other bearings. A track B has been placed lengthwise of the bed A and is rigidly secured 5 to said bed, and on this track a carriage B' is slid by the movement of the pressure-piston A'. The carriage B' is in the form of a vertical yoke, and between the arms B² and B³ thereof and free to turn in its bearings therein I have 10 mounted a hollow mandrel B⁴, the outer diameter and conformation of which mandrel are identical with the diameter and conformation of that portion of a car-journal with which the finished brass is intended to be in contact. 15 Gear-teeth B⁵ are formed in a circle near the outer periphery of the upper end of the mandrel B⁴, and central openings B⁶ and B⁷ at the upper and lower ends, respectively, of the said mandrel B⁴ provide for the ingress and egress 20 of water to cool the mandrel. A pinion C meshes with the gear-teeth B⁵ at the upper end of the mandrel B⁴, and the drive-shaft C' supports and imparts motion to said pinion C. 25 As it is contemplated that the shells of brasses may be filled with their antifriction alloy filling while being held in position on the press and that the facing of antifriction metal be there applied to brasses intended for such facing, it is necessary that the joints 30 between the brass-shells and the mandrel be made tight, and to provide for this the two vertical bars C² have been supplied. These bars are spring-sustained on the coil-springs C³ and C⁴, the former holding the bars C² to 35 ward the mandrel B⁴ and the latter toward the form-seat A³. When the piston A' is caused to move forward, the vertical bars C², held at all times in contact with the periphery of the mandrel B⁴, meet and touch the 40 edges of the form-seat A³ before the mandrel reaches its final position.

The brass D (illustrated in Fig. 4) is one faced with antifriction metal. This facing D' is given the brass in a separate mold or 45 in the press illustrated and described, in which latter case the mandrel B⁴ is moved to a position adjacent to the face of the brass body portion D² and the antifriction metal poured into the interstice between the mandrel and 50 the said body D², the vertical bars C² preventing the metal from escaping at the sides. When the antifriction metal facing D' is "set" 55 within the body D², the pressure of the apparatus exerted through the mandrel B⁴ is brought to bear upon the bearing-surface of the brass D. This pressure is so great that the metals, both the antifriction metal facing and the brass of the body D² of the casting, are condensed and their component atoms 60 forced into closer proximity, thus giving to the brass the initial embedment-pressure. In the form of brass illustrated in Fig. 4 D³ is the projecting flange at the forward end of the said brass.

65 The brass E (illustrated in Fig. 5) is a shell brass or a brass cast with a recess within the body E', which recess is intended to be filled

with an antifriction metal E², either in a mold distinct and apart from that of the press apparatus or within the press and against the 70 mandrel B⁴. In either case, however, the initial embedment-pressure is to be given the metal by means of the press, as indicated in the preceding paragraph. E³ is the projecting flange at the forward end of the brass. 75 This flange is common to all forms of brasses.

In Fig. 6 is illustrated a solid brass F. Here F' is the body, and F² is the flange at the forward end of the brass. This form of brass is prepared by casting either in sand or metal 80 molds separate from the press or in the mold formed in the press by the removable form-seat A³ and the mandrel B⁴. The initial embedment-pressure is given to the solid brass the same as to those faced or filled with anti-friction metal. When the brass F (shown in Fig. 6) is cast in a sand mold, the casting must be thoroughly cleaned before the brass is placed in the press. Brasses prepared by 85 boring or grinding may also receive their initial embedment-pressure and be shaped accurately in the press apparatus described.

I have provided the gearing B⁵ and C in order to rotate the mandrel B⁴ and planish the bearing-surface of the brass, either the solid 95 brass or the antifriction-metal variety, this rotation being imparted to the mandrel by the rotation of the drive-shaft C' after a portion of the initial embedment-pressure has been withdrawn. The surface thus obtained is 100 equal to that of a bearing which has had sufficient wear to run with the least possible friction.

My invention contemplates the preparation of all kinds of machinery bearings in the manner hereinbefore described and is not limited to the journal-bearings of railway-cars alone. 105

I claim as my invention—

1. As a new article of manufacture, a journal-bearing the molecular structure of the 110 bearing-surface of which is made dense by a means independent of the pressure of the load upon said bearing when the same is in actual use, which means exerts a pressure upon said bearing-surface greater than the 115 weight of the load upon said bearing when in actual use.

2. As a new article of manufacture, a journal-bearing, the molecular structure of the bearing-surface and body of which is made 120 dense by a means independent of the pressure of the load upon said bearing when the same is in actual use, which means exerts a pressure upon said bearing-surface greater than the weight of the load upon said bearing when 125 in actual use.

3. As a new article of manufacture, a journal-bearing, the molecular structure of the bearing-surface of which is made dense by a means independent of the pressure of the load 130 upon said bearing when the same is in actual use, which means exerts a pressure upon said bearing-surface greater than the weight of the load upon said bearing when in actual

use, and the bearing-surface of which finished bearing is composed of the smooth outer skin of the metal.

4. As a new article of manufacture, a journal-bearing having a body portion and a metallic facing for the bearing-surface, the molecular structure of which facing is made dense by a means independent of the pressure of the load upon said bearing when the same is in actual use, which means exerts a pressure upon said facing greater than the weight of the load upon said bearing when in actual use.

5. As a new article of manufacture, a journal-bearing having a body portion and a metallic facing for the bearing-surface, the molecular structure of which facing is made dense by a means independent of the pressure of the load upon said bearing when the same is in actual use, which means exerts a pressure upon said facing greater than the weight of the load upon said bearing when in actual use.

25 6. As a new article of manufacture, a journal-bearing having a recessed body portion and a metallic filling therefor, the molecular

structure of which filling is made dense by a means independent of the pressure of the load upon said bearing when the same is in actual use, which means exerts a pressure upon said filling greater than the weight of the load upon said bearing when in actual use.

7. As a new article of manufacture, a journal-bearing having a recessed body portion and a metallic filling therefor, the molecular structure of which filling is made dense by a means independent of the pressure of the load upon said bearing when the same is in actual use, which means exerts a pressure upon said filling greater than the weight of the load upon said bearing when in actual use, the bearing-surface of which filling is composed of the smooth outer skin of the metal:

20 8. As a new article of manufacture, a journal-bearing having its bearing-surface made to conform to the journal for which it is intended by pressure exerted upon said bearing-surface through a mandrel identical in conformation with said journal.
